US0D1099983S

(12) **United States Design Patent** (10) **Patent No.:** **US D1,099,983 S**
(45) **Date of Patent:** **** Oct. 28, 2025**

(54) **HARVESTER VEHICLE**

(71) Applicant: **Deere & Company**, Moline, IL (US)

(72) Inventors: **Shantanu S. Acharya**, Pune (IN);
Samir M. Mahadik, Pune (IN); **Vivek C. Vedpathak**, Pune (IN); **Felix Nagelin**, Malibu, CA (US); **Tobias Adami**, Munich (DE)

(73) Assignee: **DEERE & COMPANY**, Moline, IL (US)

(**) Term: **15 Years**

(21) Appl. No.: **29/873,247**

(22) Filed: **Mar. 28, 2023**

(30) **Foreign Application Priority Data**

(57) **CLAIM**

The ornamental design for a harvester vehicle, as shown and described.

DESCRIPTION

FIG. 1 is a front perspective view of a harvester vehicle according to our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines in the drawings illustrate portions of the harvester vehicle that form no part of the claimed design.

1 Claim, 6 Drawing Sheets
